[57] CLAIM

The ornamental design for a display holder for audio
and video cassettes or the like, as shown and described.

DESCRIPTION

FIG. 1 is a perspective view of a display holder for
audio and video cassette or the like, showing my new
design;

FIG. 2 is a top plan view thereof;

FIG. 3 is a front elevational view thereof; and

FIG. 4 is a right side, elevational view, the left side
being a mirror image thereof.

FIG. 1

FIG. 2

FIG. 3

FIG. 4
